(57) CLAIM

The ornamental design for a glove, as shown and described.

DESCRIPTION

FIG. 1 is a front view of a glove showing our new design; FIG. 2 is a rear view of the glove; FIG. 3 is a right side view of the glove; FIG. 4 is a left side view of the glove; FIG. 5 is a top view of the glove; FIG. 6 is a bottom view of the glove; and, FIG. 7 is a top front side perspective view of the glove. The broken lines illustrate boundaries of the claim and form no part of the claimed design.
